US0D1113911S

(12) **United States Design Patent** (10) **Patent No.:** **US D1,113,911 S**
(45) **Date of Patent:** ** *Feb. 17, 2026

(54) **ELECTRONIC DEVICE**

(71) Applicant: **Samsung Electronics Co., Ltd.**,
Suwon-si (KR)

(72) Inventors: **Dongkyun Kim**, Suwon-si (KR);
Namhyun Kang, Suwon-si (KR); **Jisu Hwang**, Suwon-si (KR); **Minah Koh**,
Suwon-si (KR)

(73) Assignee: **Samsung Electronics Co., Ltd.**,
Suwon-si (KR)

(*) Notice: This patent is subject to a terminal disclaimer.

(**) Term: **15 Years**

(21) Appl. No.: **29/897,390**

(22) Filed: **Jul. 14, 2023**

(30) **Foreign Application Priority Data**

Apr. 24, 2023 (KR) 30-2023-0015722

(57) **CLAIM**

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an enlarged view of the encircled portion ‘9’ in FIG. 4.

The evenly-dashed broken lines in the figures depict portions of the electronic device that form no part of the claimed design.

The dot-dot-dash broken lines encircling portions of the claimed design that are illustrated in enlargements form no part of the claimed design.

1 Claim, 7 Drawing Sheets
